US00D953992S

(12) **United States Design Patent** (10) **Patent No.:** **US D953,992 S**
(45) **Date of Patent:** **** Jun. 7, 2022**

(54) **ADAPTER FOR CONNECTING A POUCH SPOUT TO A TUBE CONNECTOR**

(71) Applicant: **FUJI SEAL INTERNATIONAL, INC.**, Osaka (JP)

(72) Inventors: **Yuma Dan**, Osaka (JP); **Hiroki Kanemitsu**, Osaka (JP)

(73) Assignee: **FUJI SEAL INTERNATIONAL, INC.**, Osaka (JP)

(**) Term: **15 Years**

(21) Appl. No.: **35/511,199**

(22) Filed: **Jul. 21, 2020**

(80) **Hague Agreement Data**

Int. Filing Date: **Jul. 21, 2020**

Int. Reg. No.: **DM/209468**

Int. Reg. Date: **Jul. 21, 2020**

Int. Reg. Pub. Date: **Jan. 22, 2021**

(57) **CLAIM**

The ornamental design for an adapter for connecting a pouch spout to a tube connector, as shown and described.

DESCRIPTION

1. Adapter for connecting a pouch spout to a tube connector
1.1 : Perspective

1.2 : Front

1.3 : Right

1.4 : Top

1.5 : Bottom

1.6 : Cross sectional

1.7 Front view, shown in an environment.

In Reproduction 1.7 the broken lines show environment only, and form no part of the claimed design.

1 Claim, 7 Drawing Sheets
